DESIGN FOR A PRESSURE COOKER

Sanford E. Richeson, Brooklyn, and Joseph A. Allegro, Maspeth, N. Y.

Application July 13, 1946, Serial No. 131,548

Term of patent 14 years

(Cl. D44—1)

To all whom it may concern:

Be it known that we, Sanford E. Richeson and Joseph A. Allegro, citizens of New York, residing in the counties of Kings and Queens, respectively, and State of New York, have invented a new, original, and ornamental Design for Pressure Cookers, of which the following is a specification, reference being had to the accompanying drawing, forming part thereof.

In the drawing

Fig. 1 is an elevational view of a pressure cooker showing my new design.

Fig. 2 is a side view thereof, and

Fig. 3 is a top plan view thereof.

We claim:

The ornamental design for a pressure cooker, as shown.

SANFORD E. RICHESON.
JOSEPH A. ALLEGRO.
